UNITED STATES PATENT OFFICE.

WILLIAM A. RAPPEPORT AND CHARLES HARDY, OF NEW YORK, N. Y.

SELF-FILLER LEVER DEVICE FOR FOUNTAIN PENS.

Application filed December 30, 1922. Serial No. 609,871.

This invention relates to a self-filler lever device for fountain pens.

An object of the invention is to provide a simple and inexpensive but highly efficient 5 means for mounting the lever.

A further object is to so construct the parts of the device that integral portions of the pen shell will be made to constitute efficient pivot elements for the lever.

10 A more detailed object is to provide a pen shell made of sheet metal, or other suitable bendable material, and to shape a part of one of the side walls of the shell so that it provides an opening to receive the lever and 15 having flanges bent inwardly and shaped to provide pivot bearings for receiving projecting pivot lugs of the lever, and the flanges standing to constitute guide elements for guiding the lever and maintaining it in 20 operative position at all times.

A further object is to provide an improved form of squeeze bar, or spring, having parts to insure its proper and efficient engagement with the lever at all times.

25 Other objects and aims of the invention, more or less specific than those referred to above, will be in part obvious and in part pointed out in the course of the following description of the elements, combinations, 30 arrangements of parts and applications of principles, constituting the invention, and the scope of protection contemplated will be indicated in the appended claims.

In the accompanying drawings which are 35 to be taken as a part of this specification, and in which we have shown merely a preferred form of embodiment of the invention:—

Figure 1 is a longitudinal sectional view 40 thru a pen shell constructed in accordance with this invention, being partly in elevation and illustrating the invention therein in association with the usual collapsible ink tube and squeeze spring.

45 Figure 2 is an enlarged detail sectional view of a portion of the shell corresponding with a portion of Fig. 1, but with the lever removed.

Figure 3 is a similarly enlarged detail side 50 view of the lever employed.

Figure 4 is a transverse sectional view also enlarged, being substantially upon the plane of line IV of Fig. 1.

55 Figure 5 is a plan view of a portion of the pen shell illustrating the condition of the same after a preliminary operation has

been performed in the production of the guide flanges, and

Figure 6 is a similar view to that shown in Fig. 5, but showing the condition of the 60 shell after the formation of the flanges has been completed but before the bending operation to complete the formation of said flanges.

Referring to the drawings for describing 65 in detail the structure which is therein illustrated, the reference character L indicates the pen shell. This may be of any size or proportions suitable for its purpose, and is preferably formed from thin sheet metal. 70 Within this shell is arranged the collapsible ink tube G for containing a supply of ink and the squeeze spring H for squeezing the tube G in the usual well known manner.

At a suitable point in the wall of the shell 75 is formed an opening 1 within which fits and operates the lever 2. The material of the shell displaced in the formation of the opening 1 is bent inwardly so as to form a pair of flanges 3 and 4 spaced apart in parallel 80 relation one at each side of the opening, and these flanges are formed with slots 5 and 6 respectively arranged opposite each other and adapted to constitute bearings for pivotally receiving a pair of pivot lugs 7 and 8 85 which project from opposite sides of the lever.

The lever may be formed in any appropriate manner but, as illustrated, is constructed from a single piece of sheet metal 90 bent into U-cross section, the flanges, or legs of the U being identical with each other and being shaped as clearly seen in Fig. 3; that is, they provide a relatively wide portion, as 9, at one end of the lever and a 95 relatively reduced, or handle portion, as 10, at the opposite end. The portion 9 has parts thereof struck out to constitute the lugs 7 and 8.

In assembling this lever in operative connection with the shell the end 9 thereof is introduced into the opening 1, being held so that the lugs 7 and 8 stand longitudinally of said opening. When the lever has been moved inwardly so that the lugs 7 and 8 clear the inner edge of the flanges, then the lever is rotated to bring the lugs into register with the slots 5 and 6. The lever is then moved outwardly to bring the lugs to rest against the inner ends of the slots 5 and 6 where they are always thereafter held by pressure from the spring H.

The spring H may be introduced into the shell, into position substantially as indicated, either before or after the introduction of the lever, but once within the shell it will be operable at all times to maintain the lugs 7 and 8 in pivot connection within the slots 5 and 6.

With the parts thus assembled the handle end of the lever may be moved at will between the two positions shown by full and dotted lines in Fig. 1. In the full line position the spring will bear against the lower edges of the flanges, or legs, 11, of the lever.

In the dotted position the spring will bear against the inner end of the lever, having been sprung downwardly by the swinging movement of the inner end of the lever. In each instance the spring always urges the pivot lugs of the lever upwardly against the upper, or closed, ends of the pivot slots.

The spring H may be of any desired form or construction, but a particular feature of the present invention consists in making that portion of the spring which engages the lever to be of cross section substantially as seen in Fig. 4; that is, so that it provides a central rib, or ridge 12 which will extend upwardly between the flanges 3 and 4 and engage the lower edges of the flanges of the lever, and so that it provides spaced grooves 13 at opposite sides of the ridge, or rib 12 into which the flanges 11 may move, and also so that it provides edge flange portions 14 for lapping upwardly about the flanges 3 and 4, said flanges 14 being preferably slightly divergent to insure their proper register with the flanges 3 and 4. A spring shaped in this manner will operate upon the lever with uniform efficiency even tho the lower edges of the flanges of the lever should not project downwardly to or below the plane of the lower edges of the flanges 3 and 4. The inevitable inaccuracies in manufacture in this regard will thus not detrimentally affect the operation of the mechanism, and on this account a less degree of care in manufacture will be required and less expense incurred for inspection and readjustment of the completed articles.

If at any time it should be necessary to remove the lever, as for the making of repairs, or otherwise, this may be readily accomplished by simply moving the lever to the dotted line position Fig. 1, and thereafter pressing it manually inward to disengage the pivot lugs from the slots, and then removing the lever by rotating it and drawing it outwardly thru the opening 1.

A portion of the material of the shell adjacent to the opening 1 is preferably inset so as to provide a seat, as 15, into which the handle end of the lever may nest when the lever is in normal, or full line, position.

It is important to note that the flanges 3 and 4 provide wall surfaces of considerable

extent at opposite sides of the opening 1, and that these are so disposed with relation to the flanges of the lever that they serve at all times to guide the lever and maintain it against likelihood of movement in any improper direction. With the lever thus guided, and at the same time having engagement with the squeeze spring H at spaced points one at each side of the center line of the ridge 12 of the squeeze spring, it is apparent that the spring will likewise be always held in proper aligned operative position.

A portion of the material of the lever between the flanges 11 at the inner end is cut away so as to provide a suitable notch, as 16, to receive the ridge 12 of the spring when the lever is in its abnormal, or squeezing, position, indicated by the dotted lines Fig. 1.

As many changes could be made in this construction without departing from the scope of the invention as defined in the following claims, it is intended that all matter contained in the above description, or shown in the accompanying drawings, shall be interpreted as illustrative only and not in a limiting sense.

Having thus described our invention, what we claim as new and desire to secure by Letters Patent is:—

1. In a self-filling fountain pen, an ink reservoir shell, a self-filler lever carried by said shell, means carried by the shell providing a pair of open ended bearings within which the lever is pivotally mounted, and a squeeze spring engaging the lever to at all times hold said pivot parts against dislodgment from said open ended bearings.

2. In a self-filling fountain pen, an ink reservoir shell having an opening therethrough, a lever pivotally mounted within said opening, a squeeze spring engaging the lever tending to hold the lever in normal swung-down position but being yieldable under pressure of the lever to allow the lever to swing to abnormal position, the lever being U-shaped in cross section and being disposed so that in its swung-down position the legs of the U project into the casing, the lever being shaped also to provide a pair of spaced projections thereon extending toward the squeeze spring when the lever is in its abnormal position, and the squeeze spring having a central longitudinal strengthening rib thereon projecting into the space between the mentioned legs and extensions and said rib providing oppositely inclining walls engaging said legs for maintaining alignment of the squeeze spring and lever in all positions of the lever.

3. In a self-filling fountain pen, an ink reservoir shell having an opening therethrough, a lever extending through said opening, the shell at opposite sides of said opening being shaped to provide a pair of

- slots therein extending substantially radially of the shell but being open at their inner ends, the outer ends being adapted to constitute bearings for the support of the lever, the lever being formed of sheet metal bent into **U** cross section and being disposed so that the legs of the **U** normally extend into the shell, and said legs having integral parts thereof bent laterally therefrom to provide pivot extensions upon the lever for engaging said bearings.
4. In a self-filling fountain pen, an ink reservoir shell having an opening therethrough, a lever extending through said opening, said lever having opposite pivot parts extending therefrom, inturned flanges formed from the material of the shell at opposite sides of said opening having bearing slots therein constituting bearings for pivotally receiving the pivot parts of the lever, and at least one of said slots being open-ended to facilitate assembly of the lever into operative position, together with a squeeze spring arranged to be operated by the lever and having engagement with the lever to retain the pivot parts of the lever in cooperative engagement within said bearings.
5. In a self-filling fountain pen, an ink reservoir shell having an opening therethrough, a lever extending through said opening the shell at opposite sides of said opening being formed with flanges projecting into the shell, said flanges having slots formed therein opening through the inner edge of said flanges and constituting bearings for the support of the lever, and pivot extensions formed rigidly upon the lever for engaging within said bearings, together with a squeeze spring arranged to be operated by the lever and having engagement with the lever to retain the pivot extensions of the lever in cooperative engagement within said bearings.
6. In a self-filling fountain pen, an ink reservoir shell having an opening therethrough, a lever extending through said opening, said lever being formed from a single elongated piece of sheet metal bent into **U**-cross section providing a pair of legs adapted to extend into the shell in the usual manner, the shell having inturned flanges within said openings arranged to provide a pivot bearing, the lever having parts of its legs intermediate the length of the lever bent laterally therefrom to provide pivot lugs pivotally engaging within said pivot bearing, a squeeze spring with which the end of the lever slidably engages during the pivotal movement of the lever, and the engagement of the squeeze spring with the lever serving to hold the pivot lugs of the lever in operative pivotal engagement with said bearing.

In testimony whereof we affix our signatures.

WILLIAM A. RAPPEPORT.
CHARLES HARDY.
